SWIMMING POOL COPING

Chris Scourtes, West Bloomfield Township, Mich.

(28875 Joy Road, Westland, Mich. 48185)

Filed Mar. 3, 1972, Ser. No. 231,773

Term of patent 14 years

Int. Cl. D25—99

U.S. Cl. D13—6

FIG. 1 is a front perspective view of a swimming pool coping showing my new design;

FIG. 2 is a fragmentary plan view thereof, on an increased scale;

FIG. 3 is a section taken in the direction of arrows 3—3 of FIG. 2;

FIG. 4 is a section taken in the direction of arrows 4—4 of FIG. 2; and

FIG. 5 is a bottom perspective view of the corner portion of the coping of FIG. 1, on an increased scale.

The broken line showing is for illustrative purposes only.

I claim:

The ornamental design for a swimming pool coping, substantially as shown and described.
